PICTURE FRAME

Filed March 8, 1929

Inventor:
Gustav Levy

UNITED STATES PATENT OFFICE

GUSTAV LEVY, OF BERLIN, GERMANY

PICTURE FRAME

Application filed March 8, 1929, Serial No. 345,419, and in Germany December 8, 1928.

My invention relates to picture frames, more particularly to such frames of the stand-up type.

According to my invention the picture or photo frame is provided on its back with rebated undercut or grooved borders or ledges into which the rear wall is slipped or inserted by means of rebate or reduced part. In this way the rear wall is held down more tightly than was possible up to now in photo-frames, so that a better protection against dust is obtained, which mainly enters from the top. This frame has the further advantage, that the rear wall may easily be re-15 moved bodily, so that the frame may be placed upon the picture to be framed and it may then be judged which size and shape is most suitable for the picture in question. The rebated or undercut borders or ledges may 20 be provided at one edge of the frame only, preferably the top, or on two opposite edges of the frame. In the former case the rear wall is closed at the bottom by a foot ledge and locked by a latch or clip member. Prefer-25 ably a recess is provided at the bottom of the rear wall into which fits a short ledge upon the frame on which the latches or clips may be conveniently mounted. This design also prevents lateral displacement of the rear wall 30 or cover plate.

An embodiment of my invention is illustrated in the annexed drawing in which

Fig. 1 is a rear view of my improved picture frame,
35 Fig. 2 is a longitudinal section through the frame in Fig. 1,

Fig. 3 is a longitudinal section like Fig. 2, but with the frame and rear wall with support separate,

40 Fig. 4 is a fractional elevation of Fig. 1.
Like numerals of reference indicate like parts in the various figures of the drawing.

In the drawing 1 is the rear wall or cover plate of the picture frame 2. This wall or plate is at one of its edges, preferably the top edge, provided with a rebate 3, which engages a corresponding rebate or groove 4 of a ledge 5 mounted at the back and near the top of the frame. Along the bottom of the frame 50 there is fixed a foot ledge 7 upon which are

fixed the latches or clips 8 for holding down the lower edge of the rear wall 1. This ledge may extend across the whole width of the picture frame, so that the entire lower edge of the rear wall 1 contacts with it, or it may be made shorter than the width of the frame, as indicated in Fig. 1 by the reference numeral 7. In the latter case the rear plate 1 is provided with projections 7', see Fig. 1 and Fig. 4, so that the ledge 7 fits into the recess 6 of the rear wall. It is obvious that in this way the rear wall 1 is prevented from becoming displaced laterally in relation to the frame.

The rear wall and the ledges may be constructed of wood, cardboard, pressed cellulose, celluloid or any other suitable material.

The rear support 9 is attached to the cover plate by a hinge 10, one member of which is provided with lateral extensions 11, which project beyond the support at both sides.

Various modifications and changes may be made without departing from the spirit and the scope of the invention, and I desire, therefore, that only such limitations shall be placed thereon as are imposed by the prior art.

I claim as my invention:

A stand-up picture frame, comprising a rebated ledge mounted at the back near the top of said frame, a short central ledge mounted at the bottom of said frame, a cover plate with a rebate at the top and a central recess at the bottom fitting said central ledge on the frame, and fastening clips mounted on said short ledge.

In testimony whereof I have affixed my signature.

GUSTAV LEVY.
